UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed October 23, 1924. Serial No. 745,299.

This invention relates to line-spacing means for typewriting machines, and there is disclosed mechanism for adjusting the platen through fractions of regular line-spaces, forwardly or rearwardly, to enable letters or figures to be written below or above the usual printing line, as when writing accents, fractions, exponents or other symbols. Devices for this purpose are illustrated in Letters 10 Patent granted to me September 2, 1913, No. 1,072,386. There is provided herein an improved and simplified device readily attachable to the machine as a unit and including a finger-lever having a pair of spaced dogs or 15 teeth. A throw of the lever, forwardly or rearwardly from a normal central position, causes one of said dogs or teeth to engage one of the teeth of the usual line-space wheel to turn the latter and the platen fractionally 20 in one direction or the other.

According to one feature of the invention, adjustable means is provided for limiting the throw of the lever in both directions, so as to adjust the printing position of the 25 exponents or symbols with relation to the letters or symbols appearing in the regular line-space.

Another feature is the provision of means for securely maintaining the lever in position when the same has been thrown forwardly or rearwardly against one or the other of its eccentric gages or stops.

Another feature is the provision of a device of the above character which is both 30 simple and inexpensive in construction, and which may be readily fitted to any standard typewriting machine by removing the left cover-plate from the platen-frame, and, without any alteration in the machine, substituting the device in place of the removed cover-plate.

A further feature embodies an arrangement whereby a plate carrying spaced dogs may be readily changed for another plate having 45 differently-spaced dogs, so as to convert the mechanism for use with a line-space wheel having an unusual number of teeth.

Other features and advantages will hereinafter appear.

50 In the accompanying drawings,

Figure 1 is a side elevation of a platen-frame and associated parts, showing my improvement in place thereon.

Figure 2 is a front view of the mechanism

shown in Figure 1, with portions broken away for clearness of illustration.

Figure 3 is a view showing the finger-lever thrown in one direction.

Figure 4 is a similar view to Figure 3, but showing the lever thrown in the opposite direction.

Figure 5 is a fragmental sectional view through a portion of the mechanism.

Figure 6 is a detail of a notched member having a dog-carrying plate attached thereto. 65

Figure 7 is a detail of a plate in which the dogs are spaced differently than in Figure 6.

A platen 10 is fast to a shaft 11 which is journaled in a platen-frame 12, and the usual type 13 are arranged to be driven toward 70 said platen to print upon a work-sheet S. A handknob 14 or the regular line-space mechanism may be utilized to turn the platen. A notched or toothed line-space wheel 15 is mounted upon the left end of the shaft 11, 75 and a detent 16 meshes with the teeth of said wheel to control the spacing of the printing lines.

In applying my improved fractional line-spacer to a typewriting machine, the usual left-hand cover-plate is removed from the platen-frame 12. A cover-plate 17, comprising a top strip 18 and a depending apron 19, is arranged to be fitted upon the left portion of the platen-frame from which the regular cover-plate was removed, and is secured in position thereon by cover-plate screws 20. The apron 19 is cut away as at 21 to provide space through which some of the parts of the device project. A bridge-piece 22 is secured upon the outer face of the apron 19 by means of screws 23, 24 and 25. A bushing 26 passes through a perforation 27 in that portion of the bridge-piece which overlies the cut-away portion 21, the bushing 95 being securely fastened therein by any means found suitable, such as riveting over the rear edges thereof into a countersunk portion 28 forming the rear edges of said perforation of the bridge-piece 22. The 100 bushing 26 provides a bearing for a stub-shaft 29 which is squared at its outer end, as indicated at 30, to receive a squared perforation of a finger-lever 31, and a screw 32 is threaded into a perforation 33 of said 105 squared portion of the stub-shaft 29 to secure said lever 31 to the stub-shaft. The rear portion of the stub-shaft 29 is reduced

so

90

95

100

105

as at 34, and passes through a perforation 35 in a substantially disk-shaped detent 36, the outer end of the reduced portion of the stub-shaft extending slightly beyond the 5 outer face of the detent 36 and being riveted over, as shown at 37, to secure same against movement upon the stub-shaft. A plate 38, having a pair of spaced dogs or teeth 39 and 40, may be secured upon the outer face 10 of the detent 36 by means of screws or soft brass rivets 41. The detent 36 has a V-shaped notch 42, which lies centrally over the stub-shaft 29 when the lever 31 is in vertical position, and is also formed with a 15 flat cam-face 42' adjacent each side of the notch 42.

In Figure 7 there is shown a plate 38^a in which the space between its dogs or teeth 39^a and 40^a is somewhat less than that of the 20 plate 38, and it is customary for a purchaser to specify the number of teeth in the line-space wheel with which the device is to be used, so that the proper plate for that particular wheel will be provided. It is obvious that a plate having teeth spaced a greater or less distance apart than those of Figure 6 may be required for use with a very different wheel as regards the number of its teeth. A detent-spring 43 has a bent-over 25 ear 44 by means of which the same is positioned upon the bridge-piece 22 and secured thereto by means of a screw 45. The free end of the detent-spring 43 is bent to form a V, as shown at 46, and is arranged to engage the V-shaped notch 42 of the detent 36, when the lever 31 is in vertical or inoperative position.

It will be noted that the teeth 39 and 40 of the detent 36 are disposed closely adjacent the teeth of the line-space wheel 15, and engage the same when the finger-lever 31 is thrown in either direction. After a regular line-space movement of the platen 10, a throw of the lever 31 in a rearward direction, as shown in Figure 3, causes the tooth 40 to engage the tooth 40' of the line-space wheel 15, and move the platen through a fraction of a line-space, so as to place the platen in position to receive typed exponents or symbols adjacent the upper portions 50 of the regular typed impressions, such as shown on the sheet S, in Figure 2. Referring to Figure 4, a throw of the lever 31 forwardly causes the tooth 39 to engage the tooth 39' on the wheel 15 and turn the platen through a fractional angle in the other direction, so as to enable exponents, or the like, to be written adjacent the lower portions or regular typed impressions. A 55 return throw of the lever from either of its fractional spacing movements to its normal central or idle position starts the platen and line-space wheel back toward initial position owing to the shape of the teeth 39 and 40, 60 which fit down into the notches between the

teeth of the wheel 15 and press against the adjacent teeth 39" and 40", respectively, of the wheel in disengaging themselves therefrom during a part of the return stroke.

A pair of eccentric disks or gages 47 and 48 lie in the path of movement of the lever 31 and are adjustably secured against the bridge-piece 22 by means of the screws 24 and 25 which pass through perforations in their respective gages. Due to the eccentricity of the gages 47 and 48, the throw of the lever 31 may be adjusted to vary the fractional angle of movement of the wheel 15, and thereby control the positions of the typed exponents or symbols up or down with 75 relation to the regular impressions with which they are associated. It will be seen that in either direction of throw of the lever 31, the detent-spring 43, after becoming disengaged from the V notch 42, presses 80 against one of the cam-faces 42' of the detent 36, which has a camming action with said detent-spring 43 to press the lever 31 firmly against one of the eccentric gages, thus eliminating any tendency of the platen to 90 move during a typing operation.

Variations may be resorted to within the scope of the invention, and portions of the improvements may be used without others.

Having thus described my invention, I 95 claim:

1. In a typewriting machine, the combination with a platen and a revoluble line-spacing mechanism, including a notched-wheel, of a fractional line-space mechanism comprising a double-acting spring, a pivoted lever movable in either direction by said spring, a pair of dogs or teeth rigid with said lever and spaced apart, so that one or the other engages with the notched-wheel when the lever is thrown in one direction or the other to turn the platen forwardly or backwardly through a fraction of a regular line-space, and adjustable stop means for limiting the throw of said lever in either 110 direction, said lever being pressed against said stop means by said spring when thrown in either direction.

2. In a typewriting machine, the combination with a platen and a revoluble line-spacing mechanism, including a notched-wheel, of a fractional line-space mechanism comprising a spring, a pivoted lever, a pair of dogs or teeth rigid with said lever and spaced apart, so that one or the other engages with the notched-wheel when the lever is thrown in one direction or the other to turn the platen forwardly or backwardly through a fraction of a regular line-space, and a pair 120 of adjustable eccentric disks for stopping the throw of said lever in either direction, said lever being continuously pressed by said spring against one of said disks upon being thrown in either direction.

3. In a typewriting machine, the combina- 130

tion with a platen and a revoluble line-spacing mechanism, including a notched-wheel, of a fractional line-space mechanism comprising a spring, a lever, a pair of dogs or 5 teeth rigid with said lever and spaced apart, so that one or the other engages with the notched-wheel when the lever is thrown forwardly or rearwardly from a normally central position, an eccentric disk for variably 10 limiting the forward throw of said lever, and an eccentric disk for variably limiting the rearward throw thereof, said lever being continuously pressed by said spring in one direction or the other upon movement of 15 the lever from normal position.

4. In a typewriting machine, the combination with a platen, a platen-frame, and a regular line-space mechanism, including a notched-wheel, of a fractional line-space 20 mechanism, including a cover-plate arranged to be secured upon the platen-frame, a lever mounted for movement on said cover-plate, a pair of dogs or teeth rigid with said lever and spaced apart, so that one or the other 25 engages with the notched-wheel when the lever is thrown in one direction or the other to turn the platen forwardly or backwardly through a fraction of a regular line-space, an eccentric stop adjacent each side of the lever 30 for variably limiting the movement thereof, and a spring for pressing said lever against said stops when thrown in either direction.

5. In a typewriting machine, the combination with a platen and a regular line-space 35 mechanism, including a notched-wheel, of a fractional line-space device including a plate arranged to be secured to the machine adjacent the notched-wheel, a bearing member fixed to said plate, a lever pivotally mounted 40 in said bearing, a detent-bearing disk secured to said lever, and further including a pair of dogs or teeth spaced apart so that one or the other engages with the notched-wheel when the lever is thrown in one direction or the 45 other to turn the platen forwardly or backwardly through a fraction of a regular line-space, an adjustable eccentric disk secured upon said plate on each side of said lever for controlling the throw of the same, and a 50 detent-spring arranged to engage said detent-bearing disk to hold said lever in a normally upright position, or to press said lever against either of said eccentric disks.

6. In a typewriting machine, the combination with a platen and a line-spacing wheel 55 therefor, of a fractional line-spacing mechanism for turning said wheel backwardly or forwardly through a part of a regular line-space, said mechanism including adjustable 60 means for controlling the degree of fractional movement of said platen in either direction selectively, and a double-acting spring, said mechanism being movable by said spring in either direction against said means.

65 7. In a typewriting machine, the combina-

tion with a platen, and a line-spacing wheel therefor, of a fractional line-spacing device arranged to be attached to the machine adjacent said wheel, said device including a lever pivoted to move backwardly or forwardly, a 70 detent-disk fixed to the lever and having two teeth and a pair of oppositely-disposed cam-faces and a notch therebetween, a double-acting leaf-spring having its free end arranged with a bend for engaging in said notch or against said cam-faces for holding said lever upright or exerting a rotatiye force thereupon, and a pair of stops for limiting the rotary movement of said lever.

8. In a typewriting machine, the combination with a platen, and a line-spacing ratchet-wheel therefor, of a fractional line-spacing device including a shaft above said ratchet-wheel, a lever pivoted on said shaft, two teeth rigid with said lever, each tooth being arranged for engaging between two consecutive teeth of said ratchet-wheel for rotating the latter either forwardly or backwardly, a disk on said shaft having oppositely-disposed cam-faces, a double-acting spring engageable with either of said cam-faces, for swinging a lever-tooth into engagement with a tooth of said ratchet-wheel and rotating the latter, and two stops for arresting to and fro movements of 95 said lever.

9. In a fractional line-spacing device for a typewriting machine, in combination, a line-spacing ratchet-wheel, a lever, two teeth rigid with said lever and arranged to engage the teeth of said ratchet-wheel for rotating the latter forwardly and backwardly by means of said lever, and means for latching said ratchet-wheel in any position to which it may be moved by said lever, said means including an adjustable stop on each side of said lever, a disk operatively connected with said lever and rotatable about the axis thereof, two oppositely-disposed cam-faces on said disk, and a double-acting spring engageable with one or the other of said cam-faces upon an initial movement of said lever.

10. In a typewriting machine, the combination with a platen and a line-spacing wheel therefor, of a fractional line-spacing device including a lever for turning said wheel forwardly or backwardly through part of a line-space, a double-acting-spring-actuated mechanism for pressing said lever, and means for adjusting the throw of said lever so as to vary the degree of fractional turning of the platen.

11. In a typewriting machine, the combination with a platen and a notched line-spacing wheel therefor, of a fractional line-spacing device comprising a plate fixed to the machine and disposed over said wheel, said plate having a portion thereof cut away, a bridge-piece secured to the plate, a bushing carried by said bridge-piece and overlying said cut-away portion, a stub-shaft extending through said bushing beyond the inner side of said plate, a 125

lever fixed upon the outer end of said stub-shaft, a detent carried by the inner end of said stub-shaft, a plate secured to said detent and including a pair of teeth spaced apart, so that 5 one or the other engages with the notched-wheel when the lever is thrown in one direction or the other to turn the platen forwardly or backwardly through a fraction of a regular line-space, a stop on each side of said lever 10 for limiting the throw thereof, and a detent-spring cooperating with said detent for holding said lever in position when thrown against either of said stops.

12. In a typewriting machine, the combination 15 with a platen and a ratchet-wheel therefor, of a fractional line-spacing device including a double-acting spring, a lever urged by said spring, and a removable plate fixed to the lever, said plate including a pair of teeth spaced apart, in accordance with the pitch of 20 the teeth of said wheel, so that one or the other operatively engages with the ratchet-wheel when the lever is thrown to turn the platen forwardly or backwardly through a fraction 25 of a regular line-space.

13. In a typewriting machine, the combination 30 with a platen and a line-spacing wheel therefor, of a fractional line-spacing device including a lever pivoted for movement adjacent said line-spacing wheel, a cam-element 35 fixed to said lever, a pair of stops for limiting the movement of said lever, double-acting resilient means co-operating with said cam-element for pressing said lever, and teeth carried by said cam-element, said teeth being spaced apart, so that one or the other engages 40 with the line-spacing wheel when the lever is thrown in one direction or the other to turn the platen forwardly or backwardly through a fraction of a regular line-space.

14. In a typewriting machine, the combination 45 with a platen and a line-spacing wheel therefor, of a fractional line-spacing device arranged to be attached to the machine adjacent said wheel, said device including a lever pivoted to move backwardly or forwardly, a cam-element fixed to said lever and having a notch in the upper portion thereof, a pair of 50 stops for limiting the forward and backward throw of said lever, and a double-acting detent-spring arranged to co-operate with said cam-element to press said lever against the selected stop, or to engage said notch to hold the lever in vertical position when out of use.

15. In a typewriting machine, the combination 55 with a platen and a regular line-space mechanism including a notched-wheel, of a fractional line-spacing device comprising a cover-plate arranged to be secured upon the typewriting machine and including a depending apron having a portion thereof cut away, a bridge-piece fixed to the outer face of said apron, a bushing secured to said bridge-piece and overlying said cut-away portion, a stub-shaft mounted in said bushing and having an

end thereof disposed adjacent each side of said apron, a lever fixed to the end of said bushing which is disposed adjacent the outer side of said apron, a detent fixed to the end of said stub-shaft adjacent the inner side of said apron, said detent having a notch therein and a pair of cam-faces, a plate secured to said detent and including teeth spaced apart, so that one or the other engages with the notched-wheel, when the lever is thrown in one direction or the other to turn the platen forwardly or backwardly through a fraction of a line-space, an adjustable stop on either side of said lever, and a detent-spring for engaging said notch to hold the lever in inoperative position, or for co-operating with said cam-faces to hold said lever against either one of its stops.

16. In a typewriting machine, the combination 70 with a platen and a line-spacing wheel therefor, of a fractional line-spacing device including a cover-plate and a depending apron, said apron being cut away approximately intermediate its ends, a lever pivoted adjacent the outer face of said apron, a shaft 75 having one end thereof secured to said lever and extending through said cut-away portion, and a pair of spaced teeth in fixed relation with the other end of said shaft, and effective to engage said line-spacing wheel to turn the 80 platen forwardly or backwardly through a fraction of a line-space.

17. In a typewriting machine, the combination 85 with a platen and a line-spacing wheel therefor, of a fractional line-spacing device 100 arranged to be secured to the machine adjacent said line-spacing wheel, said device including a lever pivoted for movement backwardly and forwardly, a pair of teeth spaced apart, so that one or the other engages with the line-spacing wheel when the lever is thrown in one direction or the other, adjustable eccentric stops for limiting the throw of the lever, a detent disk fixed to the lever and having a pair of cam-faces and a notch therebetween, and a double-acting detent-spring effective to co-operate with said cam-faces to press the lever against the selected stop, or to engage said notch to hold the lever in position, when out of use.

18. A universal unitary fractional line-spacing device adapted for use upon any of a number of typewriting machines having like platens, like platen-frames, and line-spacing ratchet-wheels, but each having a different 110 number of ratchet-wheel teeth, said device including a mounting plate arranged for being detachably mounted on any of said platen-frames, adjustable instrumentalities on said mounting plate for fractionally line-spacing 115 in either direction the ratchet-wheel of any of said machines, and a spring actuated means for holding any one of said platens securely in any fractional line-space position to which it may be moved by said instrumentalities.

19. For use with a typewriting machine having a platen-frame, a platen, and a line-spacing ratchet-wheel, a new article of manufacture including a universal unitary fractional line-spacing device which includes a mounting plate for detachably fastening on the platen-frame, and adjustable line-spacing instrumentalities on said mounting plate arranged for engaging the teeth of said ratchet-wheel, rotating the latter with the platen a variable fraction of a line-space in either direction, and securely holding the platen in its new position.
20. In a typewriting machine, in combination, a pivoted lever, an adjustable stop on each side of said lever for arresting the movement thereof, two oppositely-disposed cam-faces having fixed relation with said lever adjacent the pivot axis thereof and having a notch between them, and a double-acting leaf-spring arranged for engaging in said notch or against the selected cam-face for holding said lever in vertical position, or pressing it continuously against the selected stop.

ALFRED G. F. KUROWSKI.
